UNITED STATES PATENT OFFICE.

FRANK A. MAGEE, OF CHELSEA, AND ANDREW GARBUZZ, OF REVERE,
ASSIGNORS TO THE MAGEE FURNACE COMPANY, OF BOSTON, MASSA-
CHUSETTS.

DESIGN FOR A HEATING-STOVE.

SPECIFICATION forming part of Design No. 17,803, dated October 18, 1887.

Application filed September 1, 1887. Serial No. 248,557. Term of patent 7 years.

To all whom it may concern:

Be it known that we, FRANK A. MAGEE and ANDREW GARBUZZ, respectively of Chelsea and Revere, in the county of Suffolk and State 5 of Massachusetts, citizens of the United States, have invented and produced a new and original Design for Stoves, of which the following is a specification, reference being had to the accompanying photographs, forming a part 10 thereof.

The photograph on Sheet 1 is a front perspective view of a stove. The photograph on Sheet 2 is a side perspective view of the stove.

15 The stove is substantially square in cross-section, and has the base A, the intermediate section, B, and the upper section, C, surmounted by a top, D. Each section has rounded corners. The section A has a base-plate, a, extending from the sides and the front of the stove-body, somewhat more at the front than at the sides, and below this plate is the stand a', comprising the legs a'', ornamented with a shell design, and between the legs are ornamental sections a'', which comprise a series of 20 figures of the same character oppositely arranged and inclined from the center of the section, and with an interrupted border above and below the same, ending with a scroll at 25 each corner. Above the plate a is the ash-pit door, the various vertical sections of which have recessed lines extending from the center of each section, excepting at the end section, where they extend to a point midway the 30 length of one section, but from one side only. The upper section of the base A also has an ornamental corner of scroll-work and a side panel, a'', comprising a central rosette and an elaborate border of curved line and scroll work. 35 The intermediate section, B, rises from the plate b. It has the front panel, b', ornamented with a regularly-curved arch, b'', having concentric radial lines, as represented in the photographs, and forming a border for a door. 40 There is worked in about each side of the door and above the door, between it and the edge of the arch, sections of leaf-work. Above the arch is a lamp, and upon each side is a rep- 45

resentation of flames and smoke. The corners of this section have a modification of the design of the corners of the lower section. 50

The side panel is well represented in the photograph on Sheet 2, and it comprises a central diamond-shaped rosette, b'', inclosed by a border, b'', the lines of which cross each other at the corners, and are then united with each other beyond the corners by straight sections, and upon each side of this border b'', extending to the square border b'', is mottled or hammered work b''. 55

The body of the upper section, C, is made of sheet metal, c, giving a smooth finished appearance to the corners and sides of the stove, excepting the parts covered by the panels. This sheet metal is represented as having the 60 horizontal bead-lines c' c''.

Upon the front of the upper section is the door-frame c', which has along its lower edge an ornamental name-plate, upon each side a narrow straight ornamental figure, with extension from each edge thereof, and at the top a medallion with scroll and hammered or mottled work on each side, which fills nearly the entire width of the panel, there being a small fancy rosette and scroll upon each side of this 65 section of the frame. 70

The door c' has a circular border about a central opening and continuous borders about four openings, one at each corner of the door, and is further ornamented by the sections of 75 scroll-work, and the whole door and frame combines the mottled or hammered work of the section B with the scroll-work of the lower section. 80

The panel c'' has four borders, c'', each of 85 which surrounds an opening and all inclosed by a square border, and within the square frame is ornamental line-work somewhat in the nature of rosettes. The frame has lower inwardly-curved corners and a name-plate, and 90 a curved upper edge flanked by two curved sections of less height. This upper section, C, is surmounted by a top, D, which has the lower ornamented section, d, of a number of small set circular or oval figures, and an upper section, d', having rich scroll-work d' at 95

each corner, with straight line-work d^3 between, and there may be placed upon the top an ornamental figure, E.

Having thus fully described our invention, 5 we claim and desire to secure by Letters Patent of the United States—

1. A design for a heating-stove, comprising a base, A, an intermediate section, B, an upper section, C, and a top, D, each of which is 10 of substantially the same size in cross-section and has rounded corners, and the first two of which have richly-ornamented sides and front, and the upper section of which is smooth finished or plain, excepting the ornamental side 15 panels and ornamental front door-frame and door, and a top section having ornamented sections d d' , the whole having the shape and ornamentation shown and described.

2. In a design for a heating-stove, the leg-base a' , comprising the stove-legs ornamented with a shell design, and the intermediate section, a^3 , ornamented with a series of vertical figures and with enlarged tops oppositely arranged and inclined from the center of each 20 section, with an upper border and a lower border ending with a scroll at each end, as shown and described.

3. In a design for a heating-stove, the side panel, a^4 , comprising a rosette inclosed in a 25 border, the ends of which are crossed and form four scrolls, as shown and described.

4. In a design for a heating-stove front, an arch surmounted by a lamp and having a representation of flames and smoke extending 30 from the upper edge of the arch, as shown and described.

5. In a design for a heating-stove, the panel comprising the diamond-shaped rosette b^3 , the border b^4 , the ends of which are crossed and

united, and the hammered-work corners b^5 , as 40 shown and described.

6. In a design for a heating-stove, the door-frame c' , having side sections ornamented with a narrow straight figure having short outwardly and upwardly diverging sections, and 45 an upper cross-plate having a central medallion and scroll-work upon each side of the medallion upon a hammered surface, and a small fancy rosette and scroll upon each side of this upper section, as shown and described. 50

7. In a design for a heating-stove, the door c^5 , having a central circular border, the small circular border at each corner, each border inclosing an aperture, and sections of scroll-work between the various borders, as shown and de- 55 scribed.

8. In a design for a heating-stove, a panel having four circular borders, c^6 , inclosed in a square border or frame, sections of line-work in the nature of rosettes at the center of the 60 panel between the four borders and between the circular borders and the square border at the corners and midway between the corners upon each side and top and bottom, as shown and described. 65

9. In a design for a heating-stove, the top D, having the lower section, d , ornamented with a line of small curved or semicircular figures, and the upper section, d' , having the rich scroll-work d' at the corners and straight line-work between the same, as shown and de- 70 scribed.

FRANK A. MAGEE.
ANDREW GARBUTT.
